No. 744,768.

Patented November 24, 1903.

UNITED STATES PATENT OFFICE.

JOSEPH KOENIG, OF TWO RIVERS, WISCONSIN, ASSIGNOR TO ALUMINUM MANUFACTURING COMPANY, OF TWO RIVERS, WISCONSIN.

COMB.

SPECIFICATION forming part of Letters Patent No. 744,768, dated November 24, 1903.

Application filed June 19, 1901. Serial No. 65,121. (No model.)

To all whom it may concern:

Be it known that I, JOSEPH KOENIG, a citizen of the United States, and a resident of Two Rivers, in the county of Manitowoc and State of Wisconsin, have invented certain new and useful Improvements in Combs; and I do hereby declare that the following is a full, clear, and exact description thereof.

My invention has for its object to provide the trade with metal combs, especially aluminium combs, each of which has the back and end teeth thereof preferably of the same thickness and the other teeth less thick from back to point than said back, although all of the teeth may be of the same thickness less than that of said back, said invention being hereinafter more particularly set forth with reference to the accompanying drawings and subsequently claimed.

Figure 1 of the drawings represents a side view of a one-piece metal comb in accordance with my invention; and Figs. 2 and 3, sectional views of the comb, these views respectively indicated by lines 2 2 and 3 3 in the first figure.

The finished one-piece comb, of ductile metal, preferably aluminium, is made to have

taper-point teeth. The end teeth *b* and back *c* of the comb are preferably of the same thickness throughout, except where each of *b* and *c* is tapered to a point; but the other teeth *d* are less thick from back to point than the back itself. However, it is within the scope of my invention to have all the teeth of the same thickness less than that of said back.

The comb is made by swaging and cutting a suitable blank and is of desirable form for the trade.

Having now fully described my invention, what I claim as new, and desire to secure by Letters Patent, is—

A finished one-piece metal comb having teeth that are less thick from back to point than the back itself.

In testimony that I claim the foregoing I have hereunto set my hand, at Two Rivers, in the county of Manitowoc and State of Wisconsin, in the presence of two witnesses.

JOSEPH KOENIG.
